UNITED STATES PATENT OFFICE.

NELSON E. FUNK, OF NEW YORK, N. Y., ASSIGNOR, BY MESNE ASSIGNMENTS,
OF ONE-HALF TO RUDOLPH F. EMMERICH, OF SAME PLACE.

PAPER-FEEDING MECHANISM.

SPECIFICATION forming part of Letters Patent No. 651,567, dated June 12, 1900.

Application filed February 18, 1898. Serial No. 670,723. (No model.)

To all whom it may concern:

Be it known that I, NELSON E. FUNK, a citizen of the United States, and a resident of New York, in the county and State of New York, have invented a new and useful Improvement in Paper-Feeding Mechanism, of which the following is a specification.

My invention relates to an improvement in paper-feeding mechanism with a view of providing means for expeditiously and accurately feeding sheets of paper one at a time from a pile to a folding-machine or other device for further manipulating it. The folding or other device or machine which is to operate on the sheet after it leaves the feeding mechanism forms no part of my present invention and is not illustrated in connection therewith, it being assumed that the sheets when passing on from the mechanism herein shown and described will be received by mechanism of any well-known or approved form for further operation. It is of importance that the sheets when, for example, they contain a number of printed pages on one or both faces should be truly and accurately fed to a folder to insure the folding at the proper intervals between the pages. It is also of material importance that the sheets be fed rapidly and without any liability of disturbing a succeeding sheet during the removal of the top sheet from a stack or pile, and it is to means for accomplishing these important results that my present invention is directed.

In the accompanying drawings, Figure 1 is a view of the feeding mechanism in side elevation: Fig. 2 is an enlarged rear end view, the lower portion of the supporting-frame being omitted. Fig. 3 is a vertical longitudinal section in the plane of line 3 3 of Fig. 2 and looking toward the right as Fig. 2 is held in reading. Fig. 4 is a partial vertical longitudinal section in the plane of line 4 4 of Fig. 2 and looking toward the right. Fig. 5 is a top plan view of the same. Fig. 6 is a partial vertical section on line 6 6 of Fig. 5. Fig. 7 is an enlarged view in detail, in rear elevation, of one of a pair of truing or alining devices. Fig. 8 is a view of the same in side elevation, showing the parts in the positions which they assume when thrown rearwardly out of engagement with a sheet. Fig.

9 is a similar view showing the positions of the parts when thrown forwardly to grip and true or aline the sheet. Fig. 10 is a similar view showing the position of the parts after the sheet has been trued or alined and pulled rearward to the point where the truing or alining devices are about to release it. Fig. 11 is an enlarged view in detail, in side elevation, of the presser-foot and sheet-lifting carriage and the parts immediately connected therewith. Fig. 11^a is a face view of the cam for operating the vertically-reciprocating laterally-rocking presser-foot bar, and Fig. 12 is a view in detail of the yielding connection between the feed-hand-supporting arm and its operating-arm.

The supporting-frame for mounting the several operating parts and for sustaining the pile or stack of sheets of paper to be fed is here shown as consisting of a pair of skeleton side frames denoted by A A, connected by suitable cross-beams, rods, or ties to hold them in the proper spaced position. The table on which the pile or stack of paper is supported is denoted by B and is movable up and down to keep the top of the pile at all times in the longitudinal plane to direct the top sheet when slid along the top of the pile onto a stationary table B' to the rear of the table B, where the sheet is trued or alined before it is finally removed from the pile.

The mechanism for raising the table B at such intervals as to keep the top of the pile of sheets in the proper horizontal plane is controlled by the height of the pile, so that it will only act to raise the table when the top of the pile by the removal of the sheets therefrom reaches a predetermined point, as low as is desired for the most efficient work. The structure and arrangement of the table-operating mechanism are as follows: A vertical shaft C is mounted in suitable bearings in one of the side frames—in the present instance in the side frame A—and is provided at its lower end with a worm c, which engages a worm-wheel c', mounted near the base of the frame and arranged to be clutched to and released from a sprocket drive-wheel c² by means of a clutch-operating lever c³. The shaft c⁴, which is arranged to operate with the sprocket-wheel c², extends across the sup-

porting-frame to the opposite side frame A', where it is provided with a sprocket-wheel corresponding to the wheel c^2 , and the arrangement of lifting-chains on that side is quite similar to that shown on the side A, viz: A lifting-chain c^5 is attached to one corner of the table B and extends thence up and over a sprocket-wheel c^6 on the frame A, thence diagonally downward to and under the wheel c^2 , and thence up to the adjacent corner of the table B, to which it is attached. A second chain c^7 extends from the front corner of the table B downward to and under a sprocket-wheel c^8 , mounted on the frame A, thence diagonally upward to and over a sprocket-wheel c^9 at the upper portion of the frame, and thence down to the adjacent rear corner of the table B, to which it is attached. Hence the rotary movement of the sprocket-wheel c^2 and its shaft when clutched to the worm-wheel c' , driven by the worm c on the shaft C, will simultaneously lift on the four corners of the table B and elevate it. The shaft C has near its upper end a ratchet-wheel c^{10} , fixed to rotate therewith. Above the ratchet-wheel there is a sleeve or collar c^{11} , loosely mounted on the shaft C and provided with a nose or abutment c^{12} and with an arm c^{13} , connected by a rod c^{14} with an eccentric c^{15} on a rotary shaft D', geared by wheels d and d' with the drive-shaft D, provided with the usual drive and loose pulleys d^2 d^3 , driven from a suitable source of power. (Not shown.) Below the ratchet-wheel c^{10} a sleeve c^{16} is loosely mounted on the shaft C and carries a spring-actuated pawl c^{17} in position to engage the ratchet-teeth on the wheel c^{10} , a pin c^{18} in position to engage the face of the nose or abutment c^{12} , and a pin c^{19} in position to engage the hook on an arm c^{20} . The sleeve c^{16} is at all times under spring tension, tending to rotate it in a direction to carry the pawl c^{17} back on the face of the ratchet-wheel to engage a preceding tooth whenever the pins c^{18} and c^{19} are both released. The spring tension is applied by means of a chain or stop c^{21} , secured to and extending around or part way around the sleeve c^{16} and having its opposite end attached to a spiral spring c^{22} , connected to the frame. The hook-arm c^{20} is attached to a short rock-shaft c^{23} , mounted in the side frame A and carrying on its inner end an operating-arm c^{24} under the control of a tappet c^{25} , which when its throw is sufficiently increased by the lowering of the pile of sheets a depresses the operating-arm c^{24} and rocks the shaft c^{23} sufficiently to release the hook-arm c^{20} from the pin c^{19} , thereby permitting the pawl-carrying sleeve c^{16} to rotate under its spring tension to engage the pawl with a preceding tooth. This action of the hook-arm is so timed that it will release the pawl-carrying sleeve at the same time the nose or abutment c^{12} is rocked away from the pin c^{18} , and hence the return movement of the nose c^{12} will push the pawl and the ratchet-wheel c^{10} one step forward,

thereby rotating the shaft C and raising the table B one step. The rocking movement of the collar or sleeve c^{11} goes on continuously under the rotary movement of the shaft D', ready at every step to do effective work, but has no effect upon the shaft C to lift the table B, excepting when the pawl-carrying sleeve c^{16} is permitted to rotate, and this takes place only when the hook-arm c^{20} is lifted enough to release the sleeve. The tappet c^{25} is operated by the drop of the arm E, which carries the feed-hand e for sliding the top sheet along the pile to the truing or alining mechanism, and this sliding movement of the sheet takes place in point of time after the sheet-lifting carriage has separated the front edge of the sheet from the pile. It will, however, be explained at this point in order to complete the explanation of the table-raising mechanism. A rock-shaft F is mounted in suitable bearings at the top of the frame and from it depend hanger-arms f f' , in which arms is loosely mounted the shaft F', on which the feed-hand-carrying arms E are mounted, one at each side of the machine. The arms E are under spring tension by springs e' , tending to depress them whenever they are permitted to drop, and they are held raised against the tension of the springs e' and permitted to drop by the action of short levers e^2 , fixed to rock with the shaft F' and having their free ends loosely engaged with the under sides of the arms E and one of them being extended in the opposite direction from the shaft F', as shown at e^3 , and connected by a link e^4 with the arm e^5 of an angle-lever loosely mounted in the shaft F and having its other arm e^6 connected by an operating-rod e^7 , provided with a yoke e^8 , with the shaft D'. The yoke e^8 has a pin e^9 projecting laterally therefrom into position to engage the periphery of a cam a^{10} , fixed to rotate with the shaft D', which by its action on the yoke e^8 rocks the angle-lever to operate, through the link e^4 , the levers e^2 to release and lift the arms E. One of the hangers—in the present instance f' —has connected therewith an operating-rod f^2 , having a yoke f^3 , carrying a pin f^4 in position to engage a cam f^5 on the shaft D' to draw the hangers f f' rearwardly, and hence the arms E, carrying the feed-hands. The return or forward movement of the hangers and feed-hands is effected by a spring f^6 , which when the arm f' is drawn rearwardly is compressed by a plunger f^7 , connected with the hanger and sliding freely in a bearing f^8 on the frame. The arm E is connected with the feed-hand e by a universal joint e^{11} of any well-known or approved form and is also connected by a link e^{12} with an operating-arm e^9 , fixed to rock with a shaft F², which carries the tappet c^{25} for releasing the hook-arm c^{20} to permit the raising of the table B. The parts are so timed that at the proper moment the arms E are permitted to drop, pressing the hands e yielding onto the top sheet and then are drawn rearwardly by the swinging of the hangers.

ff' to slide the sheet to the truing mechanism. When by the successive removal of the sheets the arms *E* are allowed to drop a predetermined distance, they will rock the shaft *F²* sufficiently to release the hook-arm *c²⁰* from the stop-pin *c¹⁹* and the lifting of the table will follow, as hereinabove described, and will automatically cease as soon as it reaches the desired level by the prompt engagement of the hook-arm *c²⁰* with the pin *c¹⁹*.

Before the feed-hands engage the top sheet to slide it to the truing mechanism it is separated at the front edge from the remaining sheets of the pile, and the remaining sheets of the pile are held firmly in position while the top sheet is being slid along. The lifting and holding mechanisms for these purposes are constructed and arranged as follows: The lifting-carriage consists of a middle roller *G*, suitably mounted in a frame *g* and provided with one or more openings *g'* in its face, leading to an air-exhaust chamber within the roller, which chamber is connected by a flexible pipe *g²* with an air-exhaust apparatus of any well-known or approved form and not shown herein. A gear-wheel *g³* is mounted to rotate with the roller *G*, and a toothed sector *g⁴* is pivoted to the frame *g* in position to engage the gear-wheel *g³*. On opposite sides of the roll *G* are supporting rollers or wheels *G' G²*, which are mounted to rotate independently of the roller *G* by their frictional contact with the sheet of paper. The rollers *G' G²* are intended to rest on the top of the pile at or near the front edge, and a bar *g⁵* extends rearwardly from the frame and is connected by a joint of any well-known form with the arm *h* of a vibrating lever pivoted at *H*, with its opposite arm *h'* in position to engage the face of an operating-cam *h²*, secured to a rotary shaft *I*, extending longitudinally of the machine. The sector *g⁴* has its operating-arm *g⁶* connected by a rod *g⁷* by a universal joint with an arm *g⁸*, depending from a supporting-bar *K*, extending lengthwise of the machine. As the lever-arm *h* is reciprocated by the cam *h²* the carriage will be moved toward and away from the front edge of the pile and the roller *G* will be positively rotated by the sector *g⁴*, the arm *g⁶* of which is held by the rod *g⁷* against longitudinal movement, while the pivotal support of the sector is moved with the carriage. The universal joints at the connections of the carriage-frame and sector with the depending arms permit the carriage to tilt and accommodate itself to any unevenness of the pile. A similar carriage is operated by a companion shaft *I'* simultaneously with the carriage hereinabove described, the two carriages being spread apart, so as to lift as nearly evenly as may be upon the opposite sides of the center of the edge of the sheet. The parts are so timed that the suction will take place where the carriages are at the front extremity of their stroke, and as they are rolled rearwardly the edge of the top sheet will be lifted and rolled partly around the

rollers *G*, the suction being cut off as soon as the presser-foot, to be hereinafter described, has engaged the pile beneath the top sheet. 70

The shafts *I I'* are each grouped with a pair of stay and supporting bars *KK'*, having their forward ends fixed in a headpiece *a'* independent of the main frame, their rear ends having a sliding engagement with a yoke-piece *L*, the branches *l l'* of which receive and rest on the shaft *D'* and their middle portions having a sliding engagement in a hanger *M*, provided with a screw-threaded stem *m*, extending through a socket in the arm *m'*, 80 fixed on a transverse supporting-bar *m²*, the said screw-threaded stems being provided with hand-wheel nuts *m³* for adjusting the hangers to hold the headpiece and parts carried thereby at the desired height. The shafts *I I'* are each provided with a worm gear-wheel *i*, which intermeshes with a corresponding worm gear-wheel *i'*, secured to rotate with the shaft *D'* intermediate of the branches *l l'* of the yoke-piece *L*. 90

By the above structure and arrangement of parts the headpiece *a'* and its similar companion headpiece, together with the shafts *I I'* and the stay and supporting bars grouped with each shaft, may be slid removably at 95 pleasure to accommodate sheets of paper of varying sizes and may be tilted on the shaft *D'* to adjust the headpieces and parts carried thereby to the height of the pile at the front edge, even though it differ from the 100 height of the rear edge, as often happens.

At their front ends the shafts *I I'* each carry a cam *N* for operating the vertically-reciprocating and laterally-rocking presser-foot bars *O*. The bars *O* are mounted in socket-pieces *a² a³* on the headpiece *a'* and are provided at their lower ends with presser-feet *o*. A collar *o'*, fixed on the bar *O*, carries a pin provided with a roller *o²* in engagement with the periphery of the cam *N*, and the socket-piece *a²* is provided with an elongated slot *a⁴*, having the necessary wind to rock the bar *O* and turn the foot *o* sidewise toward the edge of the pile while a sheet is being lifted. A pin *o³*, set in the bar *O*, projects into the slot *a⁴* 115 to cause the bar to follow the wind of the slot as the bar is raised and lowered by the cam *N*. A spring *o⁴*, connected at one end with a collar *o⁵*, fixed on the bar *O*, and at its opposite end with the socket-piece *a²*, serves to hold 120 the bar *O* at all times depressed as far as the cam *N* will permit.

In operation the action of the presser-foot is so timed that it will be lifted and turned to one side during the lifting of the edge of 125 the top sheet by the lifting-carriage and will then be turned into position over the pile during its downward movement into engagement with the pile, thereby holding all but the top sheet in position during the rearward movement of the top sheet. To further insure a perfect separation of the top sheet alone from those beneath it, an air-blast is directed 130 against the front edges of the uppermost

- sheets through a pipe P , provided with a nozzle p and coupled to a supply-pipe p' , leading to an air-forcing apparatus of any well-known or approved form. (Not shown.)
- 5 The air-blast is directed against the edges at the moment the suction takes place on the lifting-carriage, so that the tendency of the top sheet to lift the one or more below it may be avoided, and to further insure the separation of those below from the top sheet in the event of two or more edges being curled up by the blast from the nozzle p I provide a second blast directed downwardly from a branch pipe p^2 onto the turned-up edge or edges of the paper after the suction has taken place, so that a sheet not positively held to the carriage by the suction will be blown away from it down onto the pile. The top sheet having been separated from those below by the lifting-carriage and slid rearwardly by the feed-hands a distance sufficient to place its rear edge on the table B' , as shown in Fig. 9, within the field of action of the truing or alining mechanism is operated
- 15 upon as follows: A bracket Q is fixed to a cross-rod a^5 of the main frame and rests, by means of a socket q , on the shaft D . An upwardly-extending portion q' of the said bracket supports the table B' at the desired height relatively to the pile of sheets a . A depending portion of the bracket supports a vibrating angle-lever pivoted at R , one arm r of which is provided with a lower clamping-jaw r' , the face of which is arranged to and from the plane of the face of the table B' from and to a position below said plane. Another arm r^2 of the vibrating lever carries a roller r^3 , held in engagement with a cam r^4 on the shaft D by a spring r^5 . (See Fig. 7.)
- 20 A vibrating arm R' is pivoted concentric with the said angle-lever which carries the lower jaw, said arm R' being held in engagement with a cam r^6 on the shaft D by a spring r^7 . The arm R' has at its free end a toothed sector r^8 , which engages a corresponding sector r^9 on the upper clamping-jaw r^{10} , pivoted to the arm r of the angle-lever. The free end of the jaw r^{10} has an extended lower lip r^{11} and a shorter upper lip r^{12} , between which
- 25 the rear edge of the paper is received as the upper jaw approaches the lower jaw to clamp the paper.
- The truing mechanism above described is one of a set of two similar mechanisms located upon opposite sides of the middle line of the path along which the sheets are fed, as shown clearly in Fig. 2, the clamping-jaws reaching the paper on the tables B' through slots in the tables. These truing mechanisms operate as follows: From the position shown in Fig. 8, assuming the paper to be in the position shown in Fig. 9 or slightly farther to the rear, the arm r is swung forwardly by the conjoint action of the spring r^5 and
- 30 cam r^4 , the engagement of the upper jaw with the toothed sector on the arm r while the

latter remains for the time being stationary serving to swing the upper jaw over toward the lower jaw, catching the rear edge of the paper between its lips and jointly with the corresponding jaw on the companion mechanism pushing the edge of the paper which may have been fed by the feed-hands askew into alinement at right angles to the path of feed. In this respect it matters not in which direction the paper be askew, as the jaws are truly alined and each will push back the edge of the sheet on its side to a point which will perfectly aline it. Just at this point, when the truing of the sheet is completed, the upper jaw by a slight depression r^{13} in the periphery of the cam r^4 is brought toward the lower jaw r' far enough to clamp the edge of the sheet of paper between them, and they are then forced rearwardly by the cam r^4 , the cam r^6 permitting the upper jaw to remain in its clamped adjustment until the arm r reaches the limit of its rearward stroke, thereby drawing the sheet of paper toward the rear, smoothing out any wrinkles which may have been caused by the truing of its edge, and leaving it perfectly alined ready for the feed-rolls to advance it for further manipulation. As soon as the arm r reaches the limit of its rearward stroke, as shown in Fig. 10, the cam r^6 begins to force the arm R' forwardly, which, by its engagement with the jaw r^{10} , rocks the latter rearwardly into the position shown in Fig. 8 below the table B' and releases it from the sheet. This leaves the way clear for the further rearward passage of the sheet under the impulse of the fast-running feed-rolls S and S' , which are so arranged that they will engage the sheet promptly after its release from the gripping-jaws of the truing mechanism. The swift-running feed-rolls are arranged in the present instance in sets of three, those in the lower set being denoted by S and those in the upper set by S' . They are fixed on shafts T and T' , the former mounted in bracket-arms t and t' , secured to the cross-rod a^4 , and the latter in arms t^2 and t^3 , fixed on a rocking shaft t^4 , mounted in extensions t^5 and t^6 of the brackets t and t' . The arm t^3 has a downward extension t^7 , the free end of which is engaged by a cam t^8 on the shaft D for rocking the shaft t^4 , and thereby lowering and raising the shaft T' , carrying the set of rollers S' toward and away from the set of rollers, to engage and release the paper. The shafts T and T' are geared together by gears s and s' , and one of them is provided with a belt-pulley s^2 for receiving a drive-belt (not shown) leading to a source of power. (Not shown.) The rollers may then be driven continuously at any speed desired and are brought into engagement with the sheet of paper by the action of the cam t^8 on the shaft D , which is so timed that it will lower the rolls S' into engagement with the sheet as soon as the truing-grippers have released it. The sheets are thus successively separated, drawn rearwardly to the truing

mechanism, alined, and finally rushed rearwardly by the feed-rolls until the pile is exhausted, when the table B may be lowered by throwing the drive sprocket-wheel c^2 out of engagement with the gear-wheel c' by the lever c^3 , a new pile placed thereon, and the operation repeated.

It is evident that changes might be resorted to in the form and arrangement of the several parts described without departing from the spirit and scope of my invention. Hence I do not wish to limit myself strictly to the structure herein set forth; but

What I claim is—

1. A movable support for a pile of sheets to be fed, means for operating the support to raise the pile, a device for sliding the top sheet along the pile, means for imparting to said device movements toward and away from the pile and back and forth along the pile and mechanism connected with the said sheet-sliding device and controlled by the movements of said device toward and away from the pile to start and stop the pile-raising means, substantially as set forth.

2. A movable support for a pile of sheets to be fed, a rotary shaft connected with the support for raising it, a ratchet-wheel secured to the shaft, a pawl, a spring-actuated rocking support for the pawl, a rocking collar or sleeve for advancing the pawl to rotate the shaft, a drive-shaft, a connection between the drive-shaft and rocking collar or sleeve, a hook-arm for holding and releasing the pawl, support, a sheet-feeding device, and means under the control of the sheet-feeding device for operating the said hook-arm, substantially as set forth.

3. The combination with a suitable support for a pile of sheets to be fed, a feeding device and means for operating it, of a sheet-lifting mechanism, a presser-foot, means for operating them, a support for the said presser-foot and sheet-lifting mechanism, and means for adjusting said support toward and away from the pile, substantially as set forth.

4. The combination with a suitable support for a pile of sheets to be fed, a feeding device and a presser-foot, of a shaft for operating the presser-foot and means for adjusting the shaft and presser-foot bodily toward and away from the pile of sheets, substantially as set forth.

5. The combination with a suitable support for a pile of sheets to be fed, a feeding device and an air-blast pipe arranged to lift the edge of the top sheet of the pile, of a movable support for said air-blast pipe and means for adjusting said movable support toward and away from the pile of sheets, substantially as set forth.

6. The combination with a suitable support for a pile of sheets to be fed, a feeding device and means for lifting the edge or edges of the upper sheet or sheets, of an air-blast arranged to assist the lifting of said edge or edges of the sheets and another air-blast arranged to

separate the upturned edges of sheets, substantially as set forth.

7. The combination with a suitable support for a pile of sheets to be fed, and a feeding device, of a carriage arranged to lift the edge of the top sheet, the said carriage carrying one or more supporting-wheels free to rotate on an axle, a roller provided with a suction-chamber and having an opening from the chamber through to its periphery, a vibrating sector geared with the said suction-roller, means for reciprocating the carriage and means for positively operating the sector and hence the suction-roller during the reciprocating movements of the carriage, substantially as set forth.

8. The combination with sheet supporting and feeding mechanism, a transversely-extending drive-shaft and means for operating it, of a lifting-carriage, a presser-foot, a longitudinally-extending shaft for operating the carriage and presser-foot, a supporting-bar, a yoke connecting the shaft and longitudinal bar with each other and forming a hinge connection with the transverse drive-shaft, and means for raising and lowering the said longitudinal shaft and bar while hinged to said shaft, substantially as set forth.

9. In combination, means for supporting a pile of sheets to be fed, a feeding device, a lifting-carriage, a presser-foot, a support for the presser-foot, a shaft for operating the presser-foot and carriage and means for adjusting the said presser-foot and carriage bodily rearward and forward and toward and away from the sheets to be fed, substantially as set forth.

10. The sheet-truing mechanism comprising a table on which the sheet may rest, a lower gripping-jaw pivoted below the table to swing back and forth along the surface of the table, an upper gripping-jaw pivoted to the arm which carries the lower jaw, a vibrating arm engaged with the pivoted upper jaw, and means for actuating the said arms to operate the jaws simultaneously and independently during each stroke of the lower jaw, substantially as set forth.

11. In combination a table for supporting a pile of sheets to be fed, a lifting-carriage for separating the edge of the top sheet from those below, a feed device for sliding the top sheet along the pile, a truing mechanism for receiving and truing the sheet before the sheet is finally removed from the pile, and feed mechanism arranged to grasp and force the sheet away from the pile when released from the truing mechanism, substantially as set forth.

In testimony that I claim the foregoing as my invention I have signed my name, in presence of two witnesses, this 11th day of February, 1898.

NELSON E. FUNK.
